UNITED STATES PATENT OFFICE.

FRANKLIN CROCKER LEWIS, OF NEW YORK, N. Y.

FOLDING TABLE.

Application filed June 11, 1923. Serial No. 644,764.

To all whom it may concern:

Be it known that I, FRANKLIN CROCKER LEWIS, a citizen of the United States, and a resident of New York, in the county of New York and State of New York, have invented certain new and useful Improvements in Folding Tables, of which the following is a specification.

This invention relates to folding tables.

10 An object of the invention is the provision of a table which is adapted to be folded into a compact unitary structure and stored in a small space when not in use.

15 A further object of the invention is the provision of a foldable frame provided with legs and a hingedly mounted table top which together with its hinge mounting is adapted to lock the frame in position when folded.

20 Another object of the invention is the provision of a foldable table provided with a shiftable top which is adapted to be located in a vertical position when the table is folded in a compact unitary structure and 25 which top may also be inclined to the horizontal for drawing purposes.

A still further object of the invention is the provision of a foldable table provided with a shiftable top and pivotally mounted 30 pockets forming a receptacle or repository for books and stationery which is located beneath the table but adapted to be locked in a forward position when the table is in use.

35 Other objects and advantages will become apparent during the course of the following description.

The invention is illustrated by way of example in the accompanying drawings, in 40 which,

Figure 1 is a front view of the folding table.

Figure 2 is an end view of the table folded in a compact unitary structure.

45 Figure 3 is an end view of the table in a position to be closed or opened.

Figure 4 is a fragmentary view in section of the telescoping legs disclosing means for locking the legs together.

50 Figure 5 is a fragmentary view in perspective disclosing more in detail the hinge connection for the top.

Figure 6 is a fragmentary view in plan of the table with the top removed.

Figure 7 is a fragmentary view in plan 55 of the table when folded.

Figure 8 is a fragmentary end view disclosing a modified form of the swingable pocket in inoperative position.

Figure 9 is a similar view with the pocket 60 or receptacle located in operative position.

Referring more particularly to the drawings, 1 designates the front hollow legs while 2 designates the rear legs. The front legs are secured together by side bars 3 and 65 the rear legs are secured together by a rear side bar 4. As shown more particularly in Figure 6 the legs are built up of flat pieces of material 5 and 6 spaced from each other by an end lug 7. The ends of the beams 3 70 and 4 are inserted between the upper ends of the bars 5 and 6 and a spacing block 8 is inserted between the end of the side bars 3 and 4 and the inner longitudinal bar 6. The ends of the side bars 3 and 4 and the 75 upper ends of the vertically disposed bars 5 and 6 and the spacing blocks are secured together in any approved manner as by screws, nails or dowel pins.

Each of the legs 1 and 2 are built as 80 described to form a hollow member and telescopically receive a solid leg 9. The leg 9 is slidable in the hollow legs and is adapted to be locked in vertical adjustment by means of a bolt 10 which passes through 85 perforations 11 in one side of the hollow leg and through alining passages 12 in the solid leg 9. At the inner ends of the passages 12 are secured threaded nuts 13. The bolts 10 are adapted to have threaded engagement 90 with said nut for clamping the solid leg 9 to the hollow legs. Secured to the lower end of the solid legs 9 are outwardly projecting feet 14 which provide an extended support for said legs and is particularly 95 adapted to prevent the table when folded in a compact unitary structure from being readily upset.

The upper ends of each pair of the legs 1 and 2 are connected by means of a pair of end bars 15 and 16 which have their inner ends hingedly connected at 17. The outer ends of the bar 15 are hingedly connected at 19 through the side bar 3 while the inner ends of the end bar 16 are hingedly connected at 19 to the rear side bar 4. The bars 15 and 16 are adapted to be alined as shown in Figures 5 and 6 when the table is located 100 105

in an operative position and the outer faces adjacent the ends of the bars 15 and 16 are in engagement with the inner edges of the spacing block 8 and the bar 6.

5 The rear side bar 4 is provided with notches 20 adjacent its ends and upon the bottom of which is secured one leaf of a hinge 21. The other end of the leaf is secured to a block 22. The block is hingedly 10 connected in each slot 20 of the side bar 4. The outer ends of the blocks are connected by means of the hinge 23 to the under face of a table top 24. The hinged connection between the table top and the rear side 15 bar 4 by means of the block 22 and the respective hinges at its opposite ends, permits the table top to be tilted not only in the position shown in Figure 5 but likewise in the position shown in Figure 2. When the 20 table is folded in a compact unitary structure the block 22 is of sufficient length to extend from one side edge of the side bar 3 to the outer edge of the side bar 4 and is adapted to be received within slots 25 and 26 in 25 the respective side bars 3 and 4 and in slots 27 and 28 in the end members which are hingedly connected together and folded inwardly as shown at Figure 7.

A brass strap 29 is provided with a slot 30 which receives a pin 30 mounted upon the side face of the blocks 20. As shown more particularly in Figure 3 a pin 31 secured to the inner face of the end member 16 is adapted to be engaged by a hook 32 on the 35 inner end of the brass strap 29.

As shown in Figure 3 a pocket or receptacle 33 is pivotally mounted at 34 on the inner projecting end of a shelf 35 which is secured to and between the rear legs 2 of 40 the supporting structure of the table. This pocket is provided with a knob 36 adapted to be grasped by the hand for pulling the pocket forwardly when it is desired to obtain anything from said pocket. The upper 45 edge of the pocket is inclined rearwardly as shown at 37 which permits easy access to the pocket and prevents articles from falling out of the same when the pocket is inclined towards the horizontal.

50 It will be seen that the hinged mounting of the pockets 33 and 34 permits the upper end of the pockets to be positioned when tilted forwardly at the front of the table.

A modified form of hinging means for the 55 pocket is shown in Figures 8 and 9. A pocket 33^a is pivotally supported by means of a hinge strap 38 connected with the sides of said pocket with its upper ends bent to form hooks and received by metal sockets 39.

60 As shown in Figure 8 when the pocket is located in a vertical position, the bottom of the same rests upon an extended shelf 40 secured to and between the rear legs 2 and project forwardly of said legs.

65 Notches 41 are formed in the hinge end

members 15 and adapted to receive the forward edge 42 of the table top 24 and in co-operation with the blocks 22 to support a table top in an inclined position whereby the same may be used as a drawing table.

70 Cleats 43 secured to the under face of the top 24 and adjacent the blocks 22 are adapted to have their outer edges alined with and engage the inner faces of the end members 15 and 16 and thereby lock the supporting structure against movement when the table is located in an operative position as shown in Figure 1.

75 The complete table in an operative position is shown in Figure 1 and when it is desired to fold the table the top is raised and located in the position shown in Figure 3. The hinge end members 15 and 16 are then moved inwardly at their hinge connection at 17 and the side members 3 and 4 are moved toward each other in parallel relation until the members 15 and 16 and said side members assume the position shown in Figure 7. The strap 29 must be released from its connection with the pin 31 before the supporting structure of the table is folded and the same is swung upwardly and placed in parallel position with the under face of the table 24. The top is then lowered together with the blocks 22, with the blocks seated in the respective notches 25, 26, 27 and 28. When the blocks 22 are seating in their respective slots the top will be swung upon its hinge connection 23 with the blocks 22 and be located in a vertical position as shown in Figure 2 with the under face of the top in close engagement with the front surfaces of the legs 1. This position of the top and the blocks 22 in their respective slots in the side members 3 and 4 and the end members 15 and 16 will lock the folded table 90 against movement.

95 What I claim is:

1. A folding table comprising a frame composed of side bars, legs rigidly connected to the side bars, end bars hinged together and having their outer ends hingedly connected to the legs, blocks hinged at one end to a side bar, a table top hinged to the other end of the blocks, whereby the top may be 100 placed horizontally or in two vertical positions adjacent the opposite side bars.

110 2. A folding table comprising a frame composed of side bars, legs rigidly connected to the side bars, end bars hinged together and having their outer ends hingedly connected to the legs, blocks hinged at one end to a side bar, a table top hinged to the other end of the blocks, and cleats secured to the 115 under face of the table top and engageable with the side bars for maintaining the frame extended, the hinging of the table top permitting said top to be placed in a vertical position at each side of the opposite side bars or in a horizontal position.

3. A folding table comprising a frame composed of side bars, legs rigidly connected to the side bars, end bars hinged together and having their outer ends hingedly connected to the legs, blocks hinged at one end to a side bar, a table top hinged to the other end of the blocks, said side bars and folding end bars being provided with notches adapted to receive the blocks when the table is folded, whereby the top may be placed horizontally or in two vertical positions adjacent the opposite side bars.

4. A folding table comprising a frame composed of side bars, legs rigidly connected to the side bars, end bars hinged together and having their outer ends hingedly connected to the legs, blocks hinged at one end to a side bar, a table top hinged to the other end of the blocks, said side bars and folding end bars being provided with notches adapted to receive the blocks when the table is folded, said top being located in a vertical position when the frame is folded in a compact unitary structure and cooperating with the blocks located in the notches for locking said frame in folded position.

5. A folding table comprising a frame composed of side bars, legs rigidly connected to the side bars, end bars hinged together and having their outer ends hingedly connected to the legs, blocks hinged at one end to a side bar, a table top hinged to the other end of the blocks, said blocks being adapted to be located transversely of the side bars and the folded-in end bars with the table top located in vertical position and in en-

gagement with the legs connected to the other side bar.

6. A folding table comprising a frame composed of side bars, legs rigidly connected to the side bars, end bars hinged together and having their outer ends hingedly connected to the legs, blocks hinged at one end to a side bar, a table top hinged to the other end of the blocks, and adapted to be positioned hingedly on the frame and vertically upon opposite sides of the side bars.

7. In a folding table, a frame composed of side bars and end bars, legs connected to the side bars, brace bars rigidly connected to the legs below the side bars, a vertically disposed pocket hingedly connected at its lower end to a brace bar and adapted to be tilted towards the other brace bar and be supported in a horizontal position at its upper end by said brace bar.

8. A folding table comprising a frame composed of side bars, legs rigidly connected to the side bars, end bars hinged together and having their outer ends hingedly connected to the legs, blocks hinged at one end to a side bar, a table top hinged to the other end of the blocks, a shelf secured to the rear legs and projecting towards the front legs, a vertically disposed pocket supported by said shelf and connected to said shelf whereby the same may be tilted forwardly towards the front legs, and a brace bar opposite the shelf and adapted to support the upper end of the pocket when disposed in a horizontal position.

FRANKLIN CROCKER LEWIS.
